CLAIM

The ornamental design for a combined fishing pole, night light and bite indicator light, as shown.

DESCRIPTION

FIG. 1 is a fragmentary rear top perspective view of the combined fishing pole, night light and bite indicator light shown in FIG. 3,

FIG. 2 is a fragmentary front top perspective view thereof;

FIG. 3 is a side elevational view of a combined fishing pole, night light and bite indicator light showing our new design;

FIG. 4 is a side elevational view of the combined fishing pole and night light thereof;

FIG. 5 is a rear perspective view of the bite indicator light; and

FIG. 6 is a front perspective view of the bite indicator light.
